SADIRON

James F. Barnes, Chicago, Ill., assignor to McGraw Electric Company, Elgin, Ill., a corporation of Delaware

Application October 27, 1948, Serial No. 149,325

Term of patent 14 years

(Cl. D49—6)

To all whom it may concern:

Be it known that I, James F. Barnes, a citizen of the United States, residing in Chicago, county of Cook, and State of Illinois, have invented a new, original, and ornamental Design for a Sadiron, of which the following is a specification, reference being had to the accompanying drawings, forming a part thereof, in which

Figure 1 is a perspective view of a sadiron, showing my new design;

Figs. 2 and 3 are side views of the iron on a reduced scale showing the handle in different positions;

Fig. 4 is a top plan view of the iron of Fig. 1; and

Fig. 5 is a front elevational view of Fig. 1.

I claim:

The ornamental design for a sadiron substantially as shown.

JAMES F. BARNES.
